UNITED STATES PATENT OFFICE.

EDWARD WALSH, JR., OF ST. LOUIS, MISSOURI.

GLASS-ANNEALING KILN.

SPECIFICATION forming part of Letters Patent No. 577,542, dated February 23, 1897.

Application filed December 17, 1894. Renewed January 23, 1897. Serial No. 620,487. (No model.)

To all whom it may concern:

Be it known that I, EDWARD WALSH, Jr., a citizen of the United States, residing at the city of St. Louis, State of Missouri, have invented a certain new and useful Improvement in Glass-Annealing Kilns, of which the following is a full, clear, and exact description, reference being had to the accompanying drawings, forming part of this specification, 55 wherein—

Figure 1 is a horizontal sectional view of my improved kiln, showing but a portion thereof; and Fig. 1^a, Sheet 2, is a similar view of a continuation of one of the kilnways. Fig. 2 is a 60 vertical longitudinal sectional view of the front portion of a kiln, and Fig. 2^a is a similar view of the continuation thereof. Fig. 3 is an enlarged fragmentary sectional view corresponding to the line of section of Fig. 2 and 65 showing the elevator in its lowered position in full lines and in dotted lines in its raised position.

This invention relates to a new and useful improvement in glass-annealing kilns of that 70 class which are particularly adapted to anneal plate-glass.

Heretofore plate-glass has been annealed in kilns or leers by passing the plate through a long way on carriages or traveling rods, the 75 plates coming out at the rear end of the kiln properly annealed. In following this old practice the temperature of the kiln determines the length of time the plate of glass should consume in passing through the kiln to be 80 properly annealed. It will thus be seen that this practice precludes the proper annealing of two or more thicknesses or sizes of plates of glass in one kiln at the same time, and as these kilns are quite expensive and take up considerable space (they being about seventy-five feet long and fifteen feet wide) it will 85 also be seen that it would be disadvantageous to construct and have in operation two or more independently-operated kilns for different thicknesses of glass, especially when the glass has to be handled from the rolling-table to the kiln and should not be chilled in transit.

The object of the present invention is to 90 construct a kiln for annealing plate-glass which will permit glass of different thicknesses to be properly annealed by being exposed to the proper temperature the proper length of time with but little more expense

than it has heretofore required to build and 55 operate a "single-thickness" annealing-kiln.

The invention may be said to consist in arranging two or more kilnways near each other, the front ends of which are connected by a neck, whereby a plate of glass may when 60 placed on the sole be introduced into its proper "way," thereby subjecting it to the proper temperature and time exposure, or the plate may, if necessary, be slid on the sole through the neck to the next way or the next, 65 as the case may be, until it reaches its proper way, when it may be pushed in on the carrying-rods, beginning its travel toward the rear end of the kiln.

A kiln constructed as shown in the drawings, involving the sliding upon the sole of the plates of glass of different thicknesses, is especially commendable when annealing plates of different thicknesses. For instance, thin glass soon cools sufficiently to be placed 70 upon the traveling bars, when it will begin its journey through the kiln. Therefore it is desirable that thin sheets be introduced into the first way, while thicker sheets, requiring, as they do, a longer time on the sole 75 of the kiln to become sufficiently cool, may be given such time while they are being slid from in front of one way to another.

Referring to the drawings, A indicates the front wall, which is provided with openings 80 or peep-holes a, through which the plates of glass may be seen and manipulated by the use of proper instruments on the sole B.

C indicates a table or ledge arranged preferably at the side of the kiln and on a level 85 with the sole B, upon which the plates of glass are placed preparatory to being shoved onto the sole B.

D indicates the side walls, which extend to the rear, upon which a suitable roof or covering E is supported. This roof is formed in sections placed so as to leave a slight space 90 between to permit the escape of heat.

Located beneath the sole B and preferably near the side walls are combustion-chambers 95 F, into which lead air and gas pipes, (shown in dotted lines, Fig. 1,) while leading from these combustion-chambers are flues G, which are preferably cross-connected at g, and which flues terminate or open into the kiln above 100 the sole B at g' and g'', the latter openings being located in the neck.

Both air and gas pipes leading to the com-

bustion-chambers F are preferably provided with dampers f, so that the passage of the air and gas to the combustion-chambers may be regulated to enable more or less perfect combustion. Combustion in the chambers F is preferably carried on slowly, or, in other words, the air and gas pipes are so regulated relative to each other that not enough oxygen is admitted to support perfect combustion. Therefore, although combustion is going on in these chambers and flues, the heat generated is comparatively small or just enough to keep the sole B to the proper temperature, while at the exits g' and g'', where abundant oxygen is supplied, perfect combustion takes place, which results in heating the air in the kiln to the proper temperature.

The mechanisms for carrying the plates of glass through the kiln form no part of this invention; but I have shown an elevator and traveling mechanism such as is shown in United States Letters Patent No. 405,527, dated June 16, 1889, granted to Brogan, Craig, and French. The elevator P is so arranged that in its lowered position it permits the plates of glass to be shoved from the sole B onto the traveling bars of the lower mechanism Q. When it is desired to place the glass on the upper traveling bars, the glass is shoved from the sole B onto the elevator and thence raised, as shown by dotted lines in Fig. 3, to such an elevation as will enable the glass to be shoved from the elevator onto the upper series of traveling bars, (lettered R in the drawings.) This elevator, as shown by dotted lines in Fig. 3, is mounted on the ends of rock-arms, the shafts of which being partially rotated in unison will raise or lower the elevator to the desired position. By this means plates of glass to be annealed are placed upon either the upper or lower traveling mechanism, as desired, and gradually traversed through the kiln.

To prevent the plates from getting chilled too much when placed on the elevator, which virtually suspends the plate in the air, I arrange a gas-pipe II, which discharges through openings h at the sides of the kilnway and above the elevator-pit, so that the temperature at this point is raised to guard against the plate cracking.

Leading beneath the floor of the kiln, preferably beneath the elevator-pit, are air and gas pipes I and J, which, when combined and ignited, burn in a combustion-chamber K. The heat from this combustion-chamber tends to heat the floor of the kiln forming the bottom of the elevator-pit, and in this manner the bottom surface of the plate of glass, when suspended on the elevator, as before referred to, is subjected to heat.

L indicates the floor of the kilnway, which extends from the sole B to the rear end of the kiln. Beneath this floor are formed flues M, which conduct the products of combustion rearwardly to stack-flues N N.

O indicates a central curtain-wall which divides the flues M into two divisions, one leading to one stack-flue and the other to another, so that when the products of combustion are drawn into the flues M by the stack-draft they are caused to spread and diffuse themselves under the floor L, as shown by the arrows, Fig. 1.

I am aware that many minor changes in the construction, arrangement, and combination of the several parts of my improved kiln may be made and substituted for those herein shown and described without in the least departing from the nature and principle of my invention.

Having thus described my invention, what I claim, and desire to secure by Letters Patent of the United States, is—

1. In an annealing-kiln, the combination with the sole, of two or more leerways leading therefrom, means for causing the travel of the glass through the leerways, an elevator located in each of said ways for receiving the glass from the sole and conveying it to the traveling mechanism, air and gas flues located beneath the sole and leading to a combustion-chamber, and flues which extend longitudinally the leerways for conducting off the products of combustion; substantially as described.

2. In an annealing-kiln, the combination with a sole, of two or more leerways leading therefrom, means for causing the travel of the glass through the leerways, an elevator located in each of said ways for receiving the glass from the sole and conveying it to the traveling mechanism, flues arranged under the sole for the slow combustion of gas, which flues terminate at points above the sole, gas-exit ports which discharge above the elevators, air and gas flues which lead beneath the elevators and combustion-chambers beneath the floors of the several leerways; substantially as described.

3. In an annealing-kiln, the combination with the sole, of two or more kilnways leading therefrom, flues arranged under said sole for the slow combustion of gas, which flues terminate at points above the sole, elevator-pits located just back of the sole, gas-exit ports which discharge into the different ways above said pits, air and gas flues which lead beneath said pits, combustion-chambers beneath the floors in the several ways, and flues for conducting off products of combustion from said chambers, which flues are divided, the divisions of the different ways leading to different stacks, substantially as described.

In testimony whereof I hereunto affix my signature, in presence of two witnesses, this 8th day of December, 1894.

EDWARD WALSII, JR.
